UNITED STATES PATENT OFFICE.

HENRY RUPPEL, OF CLEVELAND, OHIO, ASSIGNOR TO AMERICAN STOVE COMPANY, OF ST. LOUIS, MISSOURI, A CORPORATION OF NEW JERSEY.

MEANS FOR RAISING COMBUSTION-TUBES ON BLUE-FLAME WICK-STOVES.

1,103,845.

Specification of Letters Patent. Patented July 14, 1914.

Application filed August 27, 1913. Serial No. 786,942.

To all whom it may concern:

Be it known that I, HENRY RUPPEL, a citizen of the United States, residing at Cleveland, in the county of Cuyahoga and State of Ohio, have invented certain new and useful Improvements in Means for Raising Combustion-Tubes on Blue-Flame Wick-Stoves, of which the following is a specification, reference being had therein to the accompanying drawing.

My invention relates to improvements in means for raising combustion tubes on blue-flame wick-stoves, and pertains more particularly to that character of stove used in my copending application Serial No. 731,901, filed November 16th 1912.

The object of my invention is to provide means whereby the combustion tubes may be raised and supported away from the wick-trough so that the oil by capillary attraction will not work its way up on the combustion tube when the stove is not in operation. It has been found that in stoves of this character, where the combustion tubes are left in a lowered position and resting in the wick-trough, the oil by capillary attraction creeps upwardly on the combustion tube. This causes the stove to smoke when first started and it is the main object of my invention to avoid this.

A still further object of my invention is to provide a simple, cheap and effective means that can be readily attached to the ordinary combustion tubes, whereby the combustion tubes may be readily raised and supported above the wick-trough.

In the accompanying drawings—Figure 1 is a side elevation of an improved burner showing the combustion tube applied thereto and partly broken away. Fig. 2 is a vertical sectional view showing the combustion tubes in their lowered position. Fig. 3 is a vertical sectional view similar to Fig. 2, showing the combustion tubes in their raised position. Fig. 4 is a perspective view of the wick-trough and perforated combustion tube in their separated position, showing the means whereby the combustion tube is raised and held away from the wick-trough.

Referring now to the drawings, 1 represents an outer wick-tube; 2 the inner wick-tube and 3 the wick therebetween. Any suitable form of wick-raising device may be used and, therefore, I have not shown this.

The upper end of the outer wick-tube 1, has an outwardly extending annular flange 4, and the upper end of the inner wick-tube 2, is provided with an inwardly extending flange 5, which, together with the flange 4, 60 forms the wick-trough proper.

Extending across the central space within the flange 5 of the wick-trough is a perforated diaphragm 6, having at its outer end an L-shaped flange 7, which extends downwardly into the flange 5 and fits against the inner wall of said flange. The outer edge of the L-shaped flange 7, is provided with a plurality of upwardly extending L-shaped prongs 8. The outwardly extending 70 ends 9 of these prongs 8, extend in the path of travel of the wick 3, as shown in Figs. 2 and 3, and this serves to limit the upward movement of the wick.

As shown, the diaphragm 6 is preferably 75 movable and the moving means consists of a central rod 10 having its upper end screw-threaded at 11. The screw threads of the rod 10 mesh with internal threads on the central portion 12, which is suitably attached 80 to the center of the diaphragm. The said central portion 12 of the diaphragm is provided with radially extending arms 13, which have their outer ends turned downwardly at 14, and engaging the outer edge 85 of the diaphragm. This construction serves to strengthen the diaphragm and firmly hold its outer edge in shape and in proper position in relation to the flange 5 of the wick-trough and also to prevent the dia-90 phragm from being warped or deflected out of shape by the heat of the flame. The said radially extending arms at a point inside of their outer ends are provided with a circular ring 15, the said arms 13 having 95 the portions 13' extending beyond the ring, the purpose of which I will now proceed to describe.

The combustion tube 16 consists of an outer solid casing 17 and of two inner concentric perforated tubes 18 and 19, spaced apart and also spaced from the outer solid casing 17. The inner perforated tube 18, adjacent its lower end is provided with a plate 20, rigidly secured to the wall there-100 of and having a central opening 21 therein, which is the usual construction of a combustion tube. Secured to the lower face of the plate 20 is a ring 22, which extends downwardly in a vertical position. This ring is 110

preferably provided with any number of ears 23 which extend upwardly through openings in the plate 20 and are turned over upon the plate whereby the ring is securely fastened to the plate. This ring is preferably made of a strip of metal having its ends secured together by a rivet 24, as is clearly shown in Fig. 4 of the drawings. By making this ring of a strip of metal, as shown, it greatly reduces the cost of the same.

The ring 22 is provided with four downwardly extending portions 25, which correspond with the four radially extending arms 13. These downwardly extending portions 25 are provided with downwardly inclined edges 26, terminating in upwardly extending edges 27. The downwardly extending portions 25 at the ends of the edges 27 are provided with downwardly extending ears or lugs 28, which form stops to engage the outer faces of the extensions 13' of the radially extending arms 13 to limit the movement of the combustion tube.

As shown in Figs. 1 and 2, the ring 22 rests upon the radially extending arms 13, and when in said position the lower ends of the perforated tubes 18 and 19 are also resting upon the bottom of the wick trough.

When it is desired to raise the combustion tubes, it is only necessary to rotate the same by the handle 29, which causes the downwardly inclined edges 26 to ride upwardly over the radially extending arms 13, until the lower edges thereof have been reached, when the arms drop into the upwardly inclined portions 27, and the lugs 28 prevent further rotation of the combustion tube. This operation as clearly illustrated in Fig. 3 of the drawings, raises the two perforated combustion tubes 18 and 19 out of the wick trough and so exposes the wick that it can be readily lighted, or after the stove has been extinguished, raises the perforated combustion tubes out of the wick trough and prevents oil by capillary attraction from creeping up on the combustion tube.

Attention is particularly directed to the fact that the ends 9 of the prongs 8 are pointed or reduced. This reducing of the ends 9 is found to be of substantial importance in a device of this character in order to prevent any substantial interruption in the continuity of the annular flame, and to facilitate the travel of the flame around the wick when it is lighted at one point which is the usual way of lighting these burners. By having the point 9 reduced substantially as here shown, the outer edge of the top of the wick is substantially uninterrupted so far as the travel of the flame is concerned there-around when it is lighted at one point, the substantially uninterrupted outer edge of the wick forming what might be termed a flame communication for the spaces of the

wick between the said prongs. By forming the prongs as here shown there are provided substantial horizontal surfaces at their inner ends to act as wick stops while their outer ends as stated, leave the outer edge of the top of the wick substantially uninterrupted so far as the travel of the flame there-around when lighted is concerned, and the reduced portion is also found to be of importance in maintaining a continuity of the flame around the top of the wick which is essential in the type of wick burners here shown (those having the perforated combustion sections) in order to maintain an even flame at the top of the perforated combustion section.

No claim is made herein broadly to the wick-stop because the generic invention of the wick-stop here disclosed is made the subject matter of my co-pending application Serial No. 731,901.

Having thus described my invention, what I claim and desire to secure by Letters Patent is—

1. The combination with a burner having a central diaphragm, upwardly extending members carried by the diaphragm, of combustion tubes having means within the central tube for engaging the upwardly extending members and raising the combustion tube above the burner.

2. The combination with a burner having a central perforated diaphragm, radially extending arms carried by the diaphragm and strengthening the same, of a combustion tube having in the center thereof a downwardly extending member having inclined edges adapted to engage the radially extending arms for raising the combustion tube above the burner.

3. The combination with a burner having a central perforated diaphragm, radially extending arms carried by the diaphragm, of a combustion tube having a horizontally arranged plate within the central tube, a vertically disposed ring carried by the plate and having inclined lower edges adapted to engage the radially extending arms of the diaphragm, whereby the rotation of the combustion tube raises the same from the burner trough.

4. The combination with a burner having a central diaphragm, radially extending arms carried by the diaphragm, a ring connecting the outer ends of the arms, of a perforated combustion tube having a downwardly extending member having inclined edges adapted to engage the radially extending arms at a point between the said ring and the inner ends of the arms, whereby the combustion tube is raised by the rotation thereof.

5. The combination with a burner having a central perforated diaphragm, radially extending arms carried by the diaphragm,

a ring connected to the arms within their outer ends, a perforated combustion tube, the inner tube having a horizontal plate attached thereto, a vertically disposed ring 5 carried by the plate and spaced from the inner combustion tube and having portions of its edges downwardly inclined and terminating in upwardly extending portions and adapted to rest upon the outer ends of 10 the radially extending arms beyond the ring.

6. The combination with a burner, having a central perforated diaphragm, radially extending arms carried by the diaphragm and engaging the outer edge thereof, a ring 15 connecting the said arms within their outer ends, of a perforated combustion tube carrying a horizontal plate above its lower end, a downwardly extending ring carried by the horizontal plate and having downwardly 20 inclined edges terminating in upwardly extending short edges and adapted to rest upon the outer end of the radial-arms, whereby the ring connecting the radial arms 25 serves as a guide for the ring carried by the combustion tube, substantially as shown and described.

7. The combination with a burner having a central diaphragm, radially extending arms carried by the diaphragm, a combus-

tion tube, a vertically disposed ring carried 30 by the combustion tube and having inclined lower edges and adapted to engage the radially extending arms of the diaphragm.

8. The combination with a burner having a central diaphragm, and upwardly extending members carried by the diaphragm of a combustion tube having a member provided with inclined edges within the central tube and adapted to engage the upwardly extending members carried by the diaphragm 35 above the burner for raising the combustion tube out of the burner.

9. The combination with a burner wick tube having a central diaphragm, a vertically movable combustion section adapted 40 to coöperate with the wick tube, members carried by the combustion section, and members above and engaging the diaphragm, one of said members having inclined edges 45 for the purpose described and both of said members located in a horizontal plane above 50 the diaphragm.

In testimony whereof I hereunto affix my signature in the presence of two witnesses.

HENRY RUPPEL.
